ATTORNEY

UNITED STATES PATENT OFFICE.

WILLIAM LANG, OF BROOKLYN, NEW YORK.

BOX-FASTENER.

SPECIFICATION forming part of Letters Patent No. 268,108, dated November 28, 1882.

Application filed May 25, 1882. (No model.)

To all whom it may concern:

Be it known that I, WILLIAM LANG, of Brooklyn, Kings county, and State of New York, have invented certain new and useful 5 Improvements in Box-Fasteners, of which the following is a specification.

The invention has reference to an improved fastening device for boxes of all kinds; and it consists of a hollow handle-casing that is pivoted to the lower face-plate of the box and acted upon by an interior spring, the pivot of the handle-casing being extended to the inside of the face-plate and provided with a fixed hook that passes through a slot of the flange 15 of the lower face-plate and engages the slotted flange of the upper face-plate of the box.

In the accompanying drawings, Figure 1 represents a perspective view of a box with an improved fastener. Fig. 2 is a detail rear elevation of the fastener. Fig. 3 is a front view of the same, the handle-casing being shown in section; and Fig. 4, a vertical traverse section on line *x x*, Fig. 2.

Similar letters of reference indicate corresponding parts.

In the drawings, A represents the lower and B the upper face-plate of my improved fastener for jewelry and other boxes. Both face-plates are provided with inwardly-extending lips or 30 flanges and are secured respectively to the body and cover of the box.

To the lower plate, A, is pivoted a hollow face-plate, C, which is acted upon by the outer end of an interior spring, *a*, that is secured at 35 one end to lower face-plate.

To the inner end of the pivot-pin *b* of the casing C is applied a fixed hook, D, that passes through a slot of the lip or flange of the lower face-plate, A, the slot and hook serving to stop the motion of the casing in sidewise direction. 40 The lip or flange of the upper plate, B, is also slotted, so that the hook D can enter and lock the same. To open the fastening, the handle-casing C is swung sidewise, as indicated by arrows in Figs. 2 and 3, so that the hook D +5 releases the upper plate, B, when the box may be opened. The handle-casing C is returned by its spring as soon as released from the pressure of the finger, and is thereby brought back, together with the hook D, into its normal 50 vertical position, the box being readily closed by pressing the lid down until the hook re-engages the slotted lip of the upper face-plate.

Having thus described my invention, I claim as new and desire to secure by Letters Patent— 55

The combination, in a box-fastener, of the lower face-plate, A, having a slotted lip or flange, a pivoted handle-casing, C, having an interior spring, *a*, and a fixed hook, D, attached to the inner end of the handle-pivot, with an 60 upper plate, B, having a slotted lip or flange for the entrance of the hook, all substantially as set forth.

In testimony that I claim the foregoing as my invention I have signed my name in presence of two subscribing witnesses.

WILLIAM LANG.
